PAINT SPRAYING MACHINE

William G. Miller, Detroit, Mich., assignor to The
R. C. Mahon Company, Detroit, Mich., a cor-
poration of Michigan

Application January 10, 1938, Serial No. 184,148

11 Claims. (Cl. 91—45)

This invention relates to machines for automatically painting irregularly shaped articles and is particularly adapted for painting automobile bodies.

The main objects of this invention are to provide an improved paint spray machine which has a wide range of operation; to provide a paint spray machine which will maintain the spraying nozzle a predetermined desired distance from the surface of the object being painted; to provide a paint spray machine which may be readily changed to paint differently shaped objects having a wide range of contour particularly in the matter of vertical height; to provide a paint spray machine which will maintain the spray nozzle substantially perpendicular to the surface being painted; to provide a paint spray machine which will apply a uniform coat of paint free from objectionable overlaps which might cause the paint to run; to provide an improved paint spray machine which will immediately cease applying the paint should the object being painted stop its movement through the machine; to provide an improved paint spray machine which may be readily synchronized with a conveyer line so as to maintain a continuous operation for maximum production; to provide a paint spray machine of wide utility and of simple and sturdy construction, and to provide a paint spray machine which will require relatively little power to operate due to the counterbalancing of the main moving part.

An illustrative embodiment of this invention is shown in the accompanying drawings, in which:

Fig. 1 is a view in side elevation of the improved machine in full lines and with a fragmentary portion thereof shown in dotted lines in a position to paint the lower rear end of an automobile body.

Fig. 2 is a view in end elevation of the same, taken from the position of the line 2—2 of Fig. 1 and looking in the direction indicated by the arrows.

Fig. 3 is a top plan view of the same.

Fig. 4 is an enlarged view partly in section and showing the carriage supporting and paint nozzle positioning tracks in elevation, the section being taken along the line 4—4 of Fig. 1.

Fig. 5 is a sectional view taken along the line 5—5 of Fig. 4, looking in the direction indicated by the arrows.

Fig. 6 is a reduced plan view of the improved paint machine and conveyer and showing a schematic wiring diagram for the various electrically operated units.

Fig. 7 is an enlarged fragmentary sectional

view taken along the line 7—7 of Fig. 5, looking in the direction indicated by the arrows.

Fig. 8 is a sectional view taken along the line 8—8 of Fig. 7, looking in the direction indicated by the arrows.

Fig. 9 is an enlarged fragmentary sectional view taken along the line 9—9 of Fig. 3, looking in the direction indicated by the arrows.

Fig. 10 is a view similar to Fig. 7, but with the 10 solenoids energized to raise the trigger control track so that paint will be sprayed from the nozzle when the carriage is moved inwardly from the ends of its trackway.

Fig. 11 is a fragmentary sectional view, taken 15 along the line 11—11 of Fig. 10, looking in the direction indicated by the arrows.

In the particular mechanism herein illustrated a supporting structure comprising a pair of horizontally spaced vertically disposed fabricated 20 structures, generally designated 15 and 16 in Fig. 2 of the drawings, are shown positioned in spaced relation at opposite sides of a conveyer trackway 11. The track 17 is adapted to have wheel cars or dollies 18 pass therealong, and it is customary to have the dollies moved by a link chain 19 shown most clearly in Figs. 2 and 6 of the drawings. Automobile bodies 20 are shown carried by the dollies 18, but it will be understood that the mechanism and apparatus herein shown and described is equally well adapted to the painting of a wide variety of articles or objects and is in no wise limited to the painting of automobile bodies.

The supporting structures 15 and 16 are of 35 substantially identical construction and comprise a plurality of vertically disposed posts 21, which, in the embodiment shown, are heavy angles and which are arranged in spaced relation one at each corner of a rectangular shaped structure. 40 Horizontally disposed top and base members 22 and 23 respectively have their respective ends secured to the upper and lower ends of the vertical posts 21 respectively by gusset plates 24. Suitable diagonal braces 25, also formed of angle 45 iron, are riveted to the gusset plates so as to give longitudinal rigidity to the structure in a plane normal to it, as viewed in Fig. 1 of the drawings. Diagonally disposed braces 26 are riveted to the inwardly extending flanges of the corner posts 21, as best illustrated in Fig. 2 of the drawings, for imparting lateral rigidity to the fabricated structure.

It will be understood, of course, that these 50 vertically disposed spaced supports may be formed from any suitable material and by any

desired construction or may be part of the building structure in which the paint machine is housed, as the sole purpose and function of these structures are to support the operating movable mechanism hereinafter to be described.

The space between the vertical supports 15 and 16 is spanned by a jack shaft 21, one end of which is journaled in axially spaced bearing boxes 28 and 29 mounted on the top horizontally disposed members of the supporting structure 15, and the other end of which is journaled in axially spaced bearing boxes 30 and 31 similarly mounted on the top of the supporting structure 16.

The jack shaft 21 supports and has pivotally mounted thereon a superstructure generally designated 32 in Fig. 1. The superstructure 32 is substantially rectangularly shaped in plan view and is formed by a pair of spaced parallel truss members generally designated 33 and 34 in Fig. 3 of the drawings, and which are held in such position by transverse members 35, 36, 37 and 38, which are rigidly secured to the side trusses by rivets and gusset plates in the usual manner of fabricating structures of this character. Diagonals 39 and 40 are also provided for imparting rigidity to the structure and a medial brace 41 is also provided, one end of which is riveted to the gusset plate 42 secured to the cross member 35, and the other end of which is riveted to a gusset plate 43 which is secured preferably by welding to the cross members 36 and 37.

As shown most clearly in Fig. 1 of the drawings, each side truss comprises a base member 44 of channel cross section, a pair of inclined members 45 and 46, one end of each of which is secured to the respective opposite ends of the base member 44, and the other ends of each of which is secured to the upper end of a vertical post 47, the lower end of which is secured to the medial part of the base member 44 by riveting two gusset plates 48 and 49 at the upper and lower ends respectively of the post 47.

The left end of the superstructure, as viewed in Fig. 1 of the drawings, is provided with a motor and reduction gear support fabricated from a plurality of plates and angles, and generally designated 50.

The superstructure is journaled on the jack shaft 27 by means of journal bearing boxes 51 and 52 which are bolted to the upper surfaces of the base members 44 of the side trusses 33 and 34 respectively. Short angle bars 53 are welded to the inner sides of the base members 44 with one flange thereof extending in alignment with and disposed oppositely to the top flange of the base member so as to provide a good bearing seat upon which the bearings 51 and 52 are bolted.

The bearing boxes 51 and 52 are located adjacent to one end of the superstructure but are spaced inwardly from such adjacent end so that the motor and reduction gearing mechanism mounted on the support 50 serve as a partial counterbalance for the superstructure.

At the apex of the side trusses, the cross members 36 and 37, opposite ends of which project beyond the sides of the superstructure, carry bearing journal boxes 54 and 55 bolted to end plates 56 and 57 respectively which are welded to the projecting ends of the cross members 36 and 37. A bearing journal box 58 is also bolted to the top surface of the gusset plate 43 and the three bearings 54, 55 and 58 are in axial alignment and have journaled therein a cam follower shaft 59, the opposite ends of which project be-

yond their respective end bearings and have rigidly keyed thereto double flanged roller wheels 60 and 61.

The rollers 60 and 61 ride upon and their flanges embrace opposite sides of vertically disposed duplicate contour cams 62 and 63 respectively which are journaled on horizontal transversely disposed countershafts 64 and 65 respectively. The countershaft 64 is journaled in a pair of axially spaced bearing journal boxes 66 and 67 which are bolted to the top of the supporting structure 15 in spaced parallel relation to the bearing boxes 28 and 29 in which jack shaft 21 is journaled. Likewise the countershaft 15 65 is journaled in a pair of axially spaced bearing journal boxes 68 and 69 which are bolted to the top of the supporting structure 16 in spaced parallel relation to the jack shaft bearing boxes 30 and 31.

Means are provided for rotating the contour cams 62 and 63 so as to swing the outer free end of the superstructure in a vertical plane and comprise an electric motor 100 geared to an adjustable speed box 101 which in turn drives a worm gear reduction unit 102. Shaft 103 of the worm reduction gear has a chain sprocket 104 keyed thereto which receives a roller link chain 105 which passes around and drives the chain sprocket 106 keyed to the jack shaft 27. The jack shaft 27 at points closely adjacent to the outer bearing boxes 28 and 31 has keyed thereto relatively small sprockets 107 and 108 respectively which receive and drive chains 109 and 110 respectively. The chains 109 and 110 pass around and drive relatively large chain sprockets 111 and 112 respectively which are keyed to shafts 64 and 65, thus transmitting a relatively slow drive to the contour cams 62 and 63 which are likewise keyed to the shafts 64 and 65.

40 The end of the superstructure opposite to that which is pivotally mounted to the space supports has a cross head, generally designated 70 in Fig. 3 of the drawings, pivotally mounted between the projecting ends 71 and 72 of the side trusses 33 and 34. The cross head 70, as shown most clearly in Fig. 8 of the drawings, comprises a horizontally disposed upper channel member 73 and a horizontally disposed lower channel member 74, both having their flanges extending upwardly, which are rigidly secured in spaced parallel relation by vertically disposed end channels 75 and 76 and angle irons 77 riveted thereto, and thus forming a rectangular structure having top and bottom and ends but with the sides open. The end channels have their flanges disposed outwardly with respect to the structure.

The upper member 73 has its opposite ends projecting beyond the vertical end channels 75 and 76 and have journal bearing boxes 78 and 79 bolted thereto in which are journaled one end respectively, of short stub shafts 80 and 81, the other respective ends of which are journaled in bearing boxes 82 and 83 respectively which are bolted to angle brackets 84 and 85 respectively and which are welded to the projecting ends 71 and 72 respectively of the side trusses.

Means are provided for rocking the cross head 70 on its pivotal support and comprise a pair of stub shafts 86 and 87, one end of each of which is journaled in bearing boxes 88 and 89 respectively which are bolted to the lower cross head member 74. The other end of each of the shafts 86 and 87 are journaled in bearing boxes 90 and 91. The bearing journal box 90 is rigidly bolted

to one end of a connecting rod 92; and the journal bearing box 91 is bolted to one end of a channel shaped connecting rod 93. The opposite end of the connecting rod 93 has a journal bearing box 94 bolted to the underside thereof in which is journaled one end of a stub shaft 95, the other end of which is rigidly mounted in the end 96 of a bell crank lever 97 which oscillates on a fixed pivot 98 by means of a rigidly mounted stub shaft 99 which is journaled in a bearing box 115 rigidly bolted to the motor and transmission support 50. The other arm of the bell crank has a double flanged roller 116 journaled between the outer ends thereof which is arranged to embrace opposite sides of and ride upon the periphery of a focusing cam 117.

The cam 117, as shown most clearly in Fig. 9 of the drawings, is mounted on a hub 118 which has a bushing 119 and which is journaled loosely on the jack shaft 27. The other end of the hub 118 is shaped to provide an integrally formed chain sprocket 120 which receives a drive chain 121. The chain 121 also passes around and is driven by a chain sprocket 122 which is keyed to the shaft 64 on an end thereof which protrudes inwardly from its bearing box 61, the sprockets 122 and 120 being of the same size so that the focusing cam 117 and the contour cam 62 are driven in synchronism and at a one to one ratio.

A helical tension spring 123 has one end thereof secured to the connecting rod 93 and the other end thereof anchored to the base member 44 of the side truss and is under tension at all times so as to swing the connecting rod to the left, as viewed in Fig. 1 of the drawings, and thereby maintain contact of the roller 116 with the periphery of the focusing cam 117.

Likewise the opposite end of the connecting rod 92 has a journal bearing box 124 rigidly bolted thereto which is journaled one end of a stub shaft 125, the other end of which is rigidly mounted to the end 126 of one arm of a bell crank lever 127. The bell crank 127 is journaled on a fixed pivot by a rigidly supported stub shaft 128 which is journaled in bearing box 129 bolted to the side truss 34. The outer end of the other arm of the bell crank 127 has a double flanged roller 130 journaled therebetween which embraces opposite sides of and rides upon the peripheral edge of a focusing cam 131.

The focusing cam 131 is a duplicate of the cam 117 and is likewise mounted upon a bushed hub which carries an integrally formed chain sprocket 132 which receives a drive chain 133. The chain 133 passes around and is driven by a chain sprocket 134 keyed to the inner protruding end of the shaft 65 so that the focusing cam 131 and contour cam 63 are driven in unison at the same speed.

A helical tension spring 135 is also provided for holding the roller 130 in contact with the focusing cam 131, one end of the spring being attached to the connecting rod 92 and the other end thereof being anchored to the lower base member of the side truss frame 34.

A horizontally disposed straight bar 136 of rectangular cross section is bolted to the flanges of the channel 75 and 76 substantially midway between the top and bottom channels 73 and 74 respectively and forms a carriage supporting trackway.

A paint spray nozzle supporting carriage is reciprocably mounted on the trackway 136 and comprises a back plate 137 of substantially rec-

tangular shape, a front plate 138 of the same shape held in spaced parallel relation to the back plate by short shafts rigidly secured to the front and back plates near the four corners thereof and upon which are journaled four double flanged rollers 139, 140, 141 and 142. The rollers 139 and 140 ride upon the top edge of the track 136 with their flanges embracing the opposite side edges thereof and the rollers 141 and 142 fit snugly against and bear upon the lower edge of the track 136 with their flanges embracing the opposite side edges of the trackway, as shown most clearly in Figs. 7 and 8.

Means are provided for reciprocating the carriage from one end to the other of its supporting trackway and comprise an electric motor 143 having a V belt pulley 144 on its armature shaft which drives a V belt 145. The belt 145 passes around and drives a V belt pulley 146 secured to one shaft of a speed reducer 147. The output shaft of the speed reducer 147 is provided with a double V belt pulley wheel which drives belts 148 which pass around and drive a similar pulley wheel secured to one end of a shaft 149 which is journaled in axially spaced bearings 150 and 151. The bearings 150 and 151 are bolted to the top surface of a pair of angles 152 and 153. The angle 152 has its opposite ends rigidly secured to the end channels 75 and 76, and the angle 153 is secured thereto so as to form a T section, with one end of the angle 153 overlapping the side flange of the end channel 76 and secured thereto, and the other end thereof secured to the side flange of a vertically disposed channel brace 154 which is rigidly secured to the side flanges of the upper and lower cross head channels 73 and 74 substantially midway of their ends.

The opposite end of the shaft 149 has a double flanged flat belt pulley wheel 155 rigidly secured thereto which receives and drives a flat belt 156. The belt 156 extends horizontally and passes around a double flanged belt idler pulley 157 which is rigidly mounted on one end of a shaft 158. The shaft 158 is journaled in axially spaced bearing boxes 159 and 160 which are bolted to the top side of horizontally extending flanges of the angle 152 and an oppositely disposed angle 161 which is secured thereto to form a T section structure, one end of which overlaps and is secured to a side flange of the end channel 75, and the other end of which is rigidly secured to the side flange of the channel brace 154.

The belt 156 has a rectangularly shaped pin support 162 riveted thereto which has a pin 163 journaled therein, as shown most clearly in Fig. 11. One end of the pin 163 is rigidly mounted in one end of a pitman arm 164, the other end of the pitman arm 164 has one end of a headed bearing pin 165 rigidly mounted thereon. The pin 165 extends through a bushed opening in a relatively thick center portion of the back plate 137 with the head thereof on the inside of the back plate, as shown most clearly in Fig. 8.

As shown most clearly in Fig. 11, the front face 65 of the front plate 138 is provided with a pair of vertically disposed slides or guideways 166 and 167 mounted thereon in spaced parallel relation which embrace a vertically movable slide plate 168, the marginal edges of which are embraced in opposed grooves 169 of the guides 166 and 167. As shown most clearly in Fig. 8, the lower end of the slide plate 168 is bent at right angles to form a horizontal portion 170, and then bent upwardly to form a vertical portion 171 in spaced parallel relationship to the plate 168. The upper end of

the upstanding portion 171 is bifurcated to provide spaced parallel arms 172 and 173, the top ends of which are secured to the depending side flanges of a channel 174, the opposite depending flange of which is secured to the top edge of the slide plate 168.

Means are provided for moving the slide plate vertically in its slotted guideways and comprise a roller 175 journaled on a headed pin 176 which is rigidly mounted in a boss 177 formed on the face of the plate 168. The roller 175 rides on the top edge of a horizontally disposed contour track 178 which is formed of a rectangularly shaped bar disposed edgewise and having its opposite ends bolted to the side flanges of the cross head end channels 75 and 76 in spaced parallel relationship thereto, filler blocks 179 and 180 being interposed.

Means are provided for holding the slide plate roller 175 yieldingly in contact with the top edge of the contour track 178 at all times during its reciprocation and comprise a helical tension spring 181, one end of which is anchored to a laterally extending flange 182 of an angle bolted to the top edge of the front carriage plate 138, and the other end of which is secured to the top end of a vertically disposed brace member 183, the lower end of which is rigidly bolted to the top side of the web of channel 174, as shown most clearly in Fig. 8.

The inner opposed edges of the arms 172 and 173 are in vertically spaced parallel relation and serve as guides for a vertically movable trigger slide control which comprises a block 184, the opposite edges of which are provided with outwardly presenting grooves which receive and embrace the opposed marginal edges of the arms 172 and 173. The rear side of the block 184 is provided with a rigidly mounted headed pin 185 upon which is journaled a roller 186, and the front face of the block has a vertically disposed arm 187 secured thereto by threaded studs 188 and 189.

The arm 187 extends downwardly from the slide block 184, and the lower end thereof is provided with a transversely disposed finger or toe 190 which is positioned to contact a roller 191 which is journaled on the outer end of a control trigger 192 of a paint spray nozzle 193.

The paint spray nozzle 193 is mounted on the front face of the upstanding part 171 of the vertically movable slide by hooking a bail 194 over a lug 195 which is mounted on the vertical slide 171 and held in position thereon by the protruding end 196 of a vertically slideable pin 197 which is slideable in spaced bosses 198 and 199 formed on the upstanding member 171. The handle 203 of the paint spray gun fits snugly between the boss 198 and a lug 198A, which embrace opposite sides thereof.

That portion of the pin 197 which is between mounting bosses 198 and 199 is surrounded by a helical compression spring 200, the lower end of which abuts against and rests upon the boss 199, and the upper end of which bears against an enlarged head 201 formed on the upper end of the pin so as to normally urge the pin upwardly to the position shown in Figs. 7 and 8. The pin extends below the lower boss 199 and is provided with an enlarged head 202 which may be conveniently grasped by an operator for pulling the pin downwardly against the action of the spring 200 so as to release the handle portion 203 of the paint spray gun and permit it to be unhooked from the lug 195.

Compressed air is supplied to the spray gun through a flexible pipe 204 and paint is supplied through a flexible pipe 205, the spray gun as a whole being of somewhat standard design and character with only slight modifications to adapt it for use in this particular environment.

Means are provided for actuating the trigger 192 through the toe 190, arm 187, slide block 184, and roller 186, and comprises a trackway 206 which is mounted in spaced parallel relationship to the contour track 178. The track 206 is contoured similarly to the track 178 except that at the opposite ends thereof the top edge upon which the roller 186 rides is vertically spaced below the top edge of the contour track 178 a greater amount than that portion of the trackway which is inward from the ends. The track 206 is mounted on the outer face of a spacer bar 207 which is secured to the outer face of the contour track 178 and is vertically slideable thereon by reason of vertically disposed mounting slots 208 which receive the headed end of threaded studs 209 which are screwed through the spacer bar 207 and into the contour track 178.

Means are provided for raising the trigger control track 206 and comprise a pair of solenoids 210 and 211 mounted at opposite ends on the front side of the cross head and having vertically movable cores 212 and 213 respectively, the lower ends of which are pivotally connected to the upper ends of links 214 and 215 respectively. The other end of link 214 is connected to one end of a substantially horizontal lever 216, the other end of which is pivoted to the upper end of an upright link 217, the lower end of which is mounted on a fixed pivot 218 of the cross head. The medial part of the lever 216 has the upper end of an upright link 219 pivoted thereto, the lower end of which is pivotally connected to one end of the trigger control track 206.

The lower end of the link 215 is connected to one end of a substantially horizontal lever 220, the other end of which is pivoted to the upper end of an upright link 221, the lower end of which is mounted on a fixed pivot 222 on the cross head frame. The medial part of the lever 220 is pivotally connected to the upper end of an upright link 223, the lower end of which is pivotally connected to the opposite end of the trigger control track 206.

Means are provided for moving the conveyer chain 19 and comprise an electric motor 224, which, through the medium of a speed reducer 225, drives a shaft 226 journaled in bearings 227 and 228 and which carries at its medial part a chain sprocket 229 around which the conveyer chain 19 passes.

Current is supplied to the motor 224 through the conductors 230 and 231, a switch 232 being provided in the conductor 231 for opening the circuit and thereby stopping the conveyer line when desired. The conductors 230 and 231 also carry current to conductors 233 and 234 which supply current to the carriage operating motor 143. A switch 235 is provided in the conductor 231 so that the circuit from that point on may be opened without stopping the conveyer mechanism.

The conductors 230 and 231 also have bridged thereto a pair of conductors 236 and 237 which supply current to the solenoids 210 and 211, a switch 238 being provided for securing individual control of this circuit. The main circuit is also extended and supplies current to the motor 100 which drives the focusing cams and con-

70 75

tour cams, and a switch 239 is also provided for securing individual control of the motor 143.

In the operation of this machine the duplicate contour cams 62 and 73 are laid out and made in such shape as to hold the free swinging end of the superstructure and paint spray nozzle carried thereby a predetermined distance from the surface of the object to be painted, such as an automobile body, as such object is passed beneath the superstructure by the conveyer. In the particular example shown, the rollers 60 and 61 which control vertical swinging movement of the superstructure rest on their respective contour cams at about the point marked by the arrow 238, as shown in Fig. 1, when the cowl of the automobile is in position to begin painting. The conveyer and paint machine are operated at the same time and are so synchronized that as the contour cams rotate, the object to be painted is passed along under the cross head of the superstructure and the paint spray nozzle is maintained in predetermined distance from the object to be painted. At the same time the duplicate focusing cams 117 and 131 are rotated in unison with the contour cams and through the medium of the bell cranks and the connecting rods 92 and 93, the cross head 70 is rocked on its pivotal supports so as to maintain the paint spray nozzle substantially perpendicular to the surface being painted in a vertical longitudinal plane.

When the superstructure has been moved to its initial starting position by rotation of the contour cams 62 and 73, the manually operable switch 235 is opened, and the conveyer, by closure of the switch 232, continues to operate to bring the object to be painted into correct starting position. At this time the switch 235 is closed as well as the switch 238 which controls the circuit to the solenoids 210 and 211 and the switch 239 which controls the carriage operating motor 143, whereupon the motor 100 is started, the carriage operating motor 143 is started and the solenoids 210 and 211 are both energized.

Energization of the solenoids will raise their respective cores upwardly and through the system of links and levers connected thereto will raise the vertically movable trigger operating track 206 from the position shown in Fig. 7 of the drawings to the position shown in Fig. 10. When the track 206 is raised to the position shown in Fig. 10, the roller 186 which rests thereon raises the slide 184, depending arm 187, and toe 190, which in turn lifts the trigger 192 upwardly but not sufficiently to turn on the supply of compressed air and paint to the spray nozzle when the carriage is adjacent the respective ends of its track. As will be seen most clearly in Fig. 10, the vertical distance between the top edge of the track 178 and the top edge of the track 206 is materially greater at the horizontal end portions than such distance is at a point inward from its ends and where the tracks begin to take the contour of the article or object to be painted. This is also clearly illustrated in Fig. 4 of the drawings where the vertically slidable control track 206 is in its downward position.

When the solenoids lift the track upwardly the extent of the length of the slots 208 formed therein, the top edge of the track 206 is substantially level with the top edge of the track 178, and when in such position the trigger 192 is lifted relatively to the spray nozzle an amount sufficient to turn on a supply of paint and compressed air when the spray nozzle is passing over

the object to be painted, but when the carriage approaches the end limits of its track, the relative vertical distance between the top edges of the tracks 178 and 206 is such that the supply of paint and compressed air is cut off.

Should the conveyer line which is carrying the objects to be painted through the paint machine, be stopped at any time by opening of the switch 232, this will automatically stop the motors 100 and 143 and de-energize the solenoids 210 and 211 and thereby immediately cut off the supply of paint and compressed air to the nozzle so as to not build up an objectionable thickness of paint at one spot on the object being painted while the conveyer line is at a standstill.

These machines are ordinarily adjusted so as to spray a very heavy but uniform coat of paint on the objects being painted, and if the supply of paint was not discontinued upon stopping of the conveyer line, the paint would quickly accumulate to the point where it would flow and thus spoil the job.

Closing of the circuit to the motor 100 causes it to drive the speed reducer unit 101, which in turn drives the worm gear speed reducer unit 102. The output shaft 103 of the reducer 102, through the medium of sprocket gear 104 keyed thereto, drives the chain 105 and drives the relatively larger sprocket wheel 106 at a reduced speed. The sprocket 106 is keyed to the jack shaft 27 and rotation thereof drives the relatively small sprockets 107 and 108 keyed thereto which drive the chains 109 and 110 respectively. The chains 109 and 110 pass around and drive the relative large sprocket wheels 111 and 112 which are keyed to the shafts 64 and 65 respectively. Rotation of the shafts 64 and 65 rotate the contour cams 62 and 63 respectively and upon which rest the rollers 60 and 61 of the cam follower shaft 59. The shaft 59 is journaled on and supports the superstructure which is pivotally supported on the jack shaft 27 as a fixed axis, and thereby rotation of the cams will swing the opposite end of the superstructure, i. e. the one which carries the cross head 70 in a vertical plane in accordance with the shape of the contour cams.

Shafts 64 and 65 have keyed thereto sprockets 122 and 123 respectively which drive chains 121 and 133 respectively. These chains pass around and drive sprockets 120 and 132, respectively, which are integrally formed at one end of hubs at the opposite ends of which are carried the focusing cams 117 and 131 respectively. These focusing cams, through the medium of their respective bell cranks, swing the connecting rods 92 and 93 endwise so as to rock or oscillate the cross head 70 on its pivotal mounting and thereby maintain the spray nozzle substantially perpendicular to the surface of the article being painted when considered in a vertical longitudinal plane.

Closing of the circuit to the carriage operating motor 143 will cause actuation of the speed reducer 147 which, through the medium of the V belts 148 and shaft 149, will rotate the double flanged belt pulley 155 and thus move the belt 156 which passes therearound and which passes around the idler 157. Movement of the belt 156 will carry the pitman arm 164 with it and thus cause reciprocation of the carriage, to which it is connected, upon the track 136 from one end thereof to the other continuously while the motor 143 is energized.

If the solenoids 210 and 211 are not energized

during the reciprocation of the carriage on its track, the paint will not be sprayed from the spray gun by reason of the fact that the trigger 192 is not raised sufficiently relative to its point of mounting, but if the solenoids are energized and the trigger control track 206 thereby raised, then the trigger will be moved sufficiently by its connecting mechanism through the medium of the roller 186 riding on the top edge of the track 206, to cause paint to be sprayed from the nozzle except at those portions of the tracks adjacent the ends thereof. Cutting off of the supply of paint at the ends of the track will result in an even and uniform coat of paint being applied to all parts of the object being carried by the conveyer as well as save much paint which would otherwise be wasted.

In the event it is desired to spray a different color of paint on the next succeeding object carried by the conveyer line, then the paint spray nozzle may be quickly removed by grasping the head 201 and pulling down on the pin 197 against the action of the spring 200, then swinging out the handle portion 203 and unhooking the bail 194 from the lug 195. A similar spray gun having the desired color of paint therein may then be quickly hooked over the lug 195 and swung into place and there retained by the upstanding end 196 of the pin, the handle portion 203 being snugly embraced between the boss 198 and the lug 198A which engages the upper side of the handle.

By adjusting the variable speed reducer 101, the operating speed of the contour and focusing cams and thereby vertical swinging movement of the superstructure may be synchronized with the conveyer line so that automobile bodies or other objects placed upon the conveyer line at uniformly spaced intervals will be in correct position to be painted without readjustment of the paint machine, as each object is carried thereto by the conveyer. In other words, the conveyer and paint machine may be so synchronized as to produce a continuous operation of painting upon articles of similar contour when placed upon the conveyer line in predetermined spaced relationship.

The circuit to the solenoids 210 and 211 may be controlled also by an electric eye or some similar means whereby the spraying of the paint will not be started until the object being painted is in correct position with respect to the paint machine and will be immediately discontinued when the object has passed therethrough and been completely painted.

Although but one specific embodiment of this invention has been herein shown and described, it will be understood that numerous details of the construction shown may be altered or omitted without departing from the spirit of this invention, as defined by the following claims.

What is claimed is:

1. A paint spray machine comprising a supporting framework, a superstructure mounted on horizontal pivots on said supporting structure and having a free end swingable in a vertical plane, a paint spray nozzle mounted on the free swinging end of said superstructure and means for swinging said superstructure on its pivotal mounting for maintaining said spray nozzle a predetermined distance from an object to be painted.

2. A paint spray machine comprising a supporting framework, a superstructure mounted on horizontal pivots on said supporting structure and having a free end swingable in a vertical

plane, a paint spray nozzle pivoted on the free swinging end of said superstructure, a contour cam supporting the free swinging end of said superstructure, and means for rotating said cam for maintaining said spray nozzle a predetermined distance from an object to be painted.

3. A paint spray machine comprising a supporting structure, a superstructure pivotally mounted on said supporting structure and having a free swinging end, said structures being arranged so that objects to be painted may be moved along under said superstructure, a paint spray nozzle mounted on the free swinging end of said superstructure for movement in a path transversely to the path of travel of the objects to be painted, means for moving said nozzle in its path of travel, a contour cam supporting the free swinging end of said superstructure, means for rotating said cam for maintaining said spray nozzle a predetermined distance from the object to be painted and means for oscillating said nozzle relative to said superstructure on an axis substantially parallel to the axis of movement of said superstructure.

25 4. A paint spray machine comprising spaced supports adapted to have a conveyer pass therebetween, a superstructure pivotally mounted on and bridging the space between said supports, contour cams journaled on said supports and 30 engaging said superstructure for controlling movement thereof on its pivotal support, a paint spray nozzle carried on one end of said superstructure and movable thereon in a path transverse to the path of movement of the conveyer, and a focusing cam journaled on one of said structures and driven in synchronism with said contour cam for moving said spray nozzle in a plane parallel to the direction of movement of the conveyor.

35 5. A paint spray machine comprising spaced supports adapted to have a conveyer line pass therebetween, a superstructure pivotally mounted on and bridging the space between said supports, a trackway pivotally carried on one end of said superstructure in spaced relation to said pivotal support, a carriage reciprocable on said trackway, a paint spray nozzle on said carriage, means for moving said superstructure to maintain said spray nozzle a predetermined distance from articles to be painted thereby, and means for rocking said trackway to secure a predetermined angularity of said nozzle with respect to the surface of the article being painted thereby.

6. A paint spray machine comprising spaced supports adapted to have a conveyer line pass therebetween, a jack shaft journaled on and bridging the space between said supports, a superstructure pivotally supported adjacent one end thereof on said jack shaft, a paint spray nozzle carried by the other end of said superstructure, contour cams journaled on said supports and driven by said jack shaft for moving said superstructure on its pivotal supports so as to maintain said nozzle a predetermined distance from objects to be painted which are carried by the conveyer line and means for driving said jack shaft.

7. A paint spray machine comprising spaced supports adapted to have a conveyer line pass therebetween, a jack shaft journaled on and bridging the space between said supports, a superstructure pivotally supported adjacent one end thereof on said jack shaft, a trackway pivotally mounted on the other end of said super-

structure, a paint spray nozzle reciprocable on said trackway in a path transverse to the path of travel of the conveyer, contour cams journaled on said supports and driven by said jack shaft for moving said superstructure on its pivotal supports so as to maintain said nozzle a predetermined distance from the surface of objects to be painted, a focusing cam journaled on said jack shaft and driven in unison with said contour cams, connections between said focusing cam and said trackway for rocking said trackway and nozzle independently of said superstructure movement and means for driving said jack shaft.

8. A paint spray machine comprising horizontally spaced supports, a conveyor line passing between said supports, a jack shaft journaled on and bridging the space between said supports, a superstructure pivoted adjacent one end thereof on said jack shaft, contour cams journaled on said supports for supporting and moving the other end of said superstructure in a vertical plane, a paint spray nozzle movably mounted on said superstructure adjacent its vertically movable end, a focusing cam and connections for oscillating said spray nozzle on a horizontal transverse axis and means for driving said contour and focusing cams in synchronism.

9. A paint spray machine comprising horizontally spaced supports, means for moving objects to be painted between said supports, a vertically swingable superstructure pivoted on said supports on a horizontal axis transverse to the direction of movement of the objects to be painted, a horizontally disposed trackway pivotally mounted on the vertically swingable end of said superstructure on a horizontal axis sub-

stantially parallel to the axis of said superstructure's pivotal mounting, a carriage reciprocable on said trackway, a paint spray nozzle carried by said carriage and means for vertically swinging said superstructure and rocking said trackways in synchronism on their respective pivotal mountings whereby said nozzle will be maintained a predetermined distance from and at a predetermined angle with respect to the surface of irregularly shaped articles to be painted.

10. In a paint spray machine, a relatively straight horizontally disposed track, a carriage reciprocable on said track, a spray nozzle holder vertically slidable on said carriage, a paint spray nozzle on said holder, a contoured track adjacent said straight track for actuating and positioning said nozzle holder, a trigger on said nozzle for controlling the flow of paint through said nozzle, a third track similarly contoured and adjacent to said second mentioned track for actuating said trigger, and means for shifting one of said contoured tracks relative to the other for actuating said trigger.

11. A paint spray machine comprising a supporting framework, a superstructure swingably mounted on said supporting framework and having a free swinging end, a paint spray nozzle pivoted on the free swinging end of said superstructure and bodily movable therewith, means for moving said superstructure on its mounting for maintaining said spray nozzle a predetermined distance from an object to be painted, and independent means for moving said spray nozzle on its pivotal mounting to maintain said spray nozzle normal to the surface of the object to be painted.

WILLIAM G. MILLER.
